US00D967866S

(12) **United States Design Patent** (10) **Patent No.:** **US D967,866 S**
(45) **Date of Patent:** **** Oct. 25, 2022**

(54) **AIR COMPRESSOR**

(71) Applicant: **Kaeser Kompressoren SE**, Coburg (DE)

(72) Inventor: **Michael Suthmann**, Kranzberg (DE)

(73) Assignee: **KAESER KOMPRESSOREN SE**, Coburg (DE)

(**) Term: **15 Years**

(21) Appl. No.: **29/824,797**

(22) Filed: **Jan. 27, 2022**

Related U.S. Application Data

(62) Division of application No. 29/722,213, filed on Jan. 28, 2020.

(57) **CLAIM**

The ornamental design for an air compressor, as shown and described.

DESCRIPTION

FIG. 1 is a top front perspective view of an air compressor in accordance with an embodiment of my new design;

FIG. 2 is a right-side elevation view of FIG. 1;

FIG. 3 is a left-side elevation view of FIG. 1;

FIG. 4 is a front elevation view of FIG. 1;

FIG. 5 is a rear elevation view of FIG. 1;

FIG. 6 is a top plan view of FIG. 1;

FIG. 7 is a bottom plan view of FIG. 1;

FIG. 8 is a right-side rear perspective view of FIG. 1; and,

FIG. 9 is a left-side front perspective view of FIG. 1.

The dash-dash broken lines depict portions of the air compressor that form no part of the claimed design.
